UNITED STATES PATENT OFFICE.

GEORGE BATY, OF BROOKLYN, AND ROBERT M. RYAN, OF NEW YORK, N. Y.

INCANDESCENT GAS-BURNER.

1,138,833.

Specification of Letters Patent. Patented May 11, 1915.

Application filed December 9, 1914. Serial No. 876,343.

To all whom it may concern:

Be it known that we, GEORGE BATY and ROBERT M. RYAN, said BATY being a subject of the King of Great Britain, said RYAN a citizen of the United States, said BATY residing at Brooklyn, in the county of Kings, and said RYAN residing at New York, county of New York, both in the State of New York, have invented a new and useful 10 Incandescent Gas-Burner, of which the following is a specification.

This invention relates to an incandescent gas burner and more particularly to a burner of the inverted type.

15 It has been heretofore customary to support the mantle and shade of an inverted burner upon the burner tube, with which arrangement it is impossible to obtain access to the burner without first removing the 20 shade and the mantle therefrom. This operation frequently results in the destruction of the delicate mantle and also involves a considerable expenditure of time and labor in separating and reassembling the parts. 25 Furthermore, it is necessary that the burner should be within the mantle when lighted. The mantle thus becomes filled with gas and upon ignition an explosion of considerable force occurs, which places an excessive strain upon the delicate structure of the 30 mantle.

It is one of the objects of our invention to provide an incandescent gas burner of the type described in which the burner tube 35 may be removed from its operative position relative to the mantle without first removing the latter from its normal position. By this construction we are enabled to light the burner while removed from the mantle to a 40 position in which the flame may be readily inspected and adjusted and we also avoid explosive injury to the mantle.

A further object of our invention is to provide an improved mantle holder by the 45 use of which the mantle may be readily removed from its operative position for inspection or cleaning. We also provide a single support for the mantle holder, the shade and the reflector so designed that any 50 one of these parts may be removed without disturbing the other two parts.

A still further object of our invention is the provision of an improved pivotal con-

nexion between the burner tube and its supporting pipe, said connection being so designed that the gas for the Bunsen burner and also for a pilot light may flow therethrough under certain definite conditions. A further feature of this part of our invention relates to the provision of means by which the pilot flame will automatically ignite the Bunsen flame as the burner is removed from its operative position relatively to the mantle and by which the pilot flame will be extinguished as the burner is re-turned to operative position.

We also provide an improved arrangement for passing the pilot tube through the Bunsen burner.

With these objects in view our invention 70 comprises certain devices, arrangements, and combination of parts which will be herein-after described and more particularly pointed out in the appended claims.

A preferred form of our invention is 75 shown in the drawings in which—

Figure 1 is a side elevation of an inverted incandescent gas burner embodying the several features of our invention; Fig. 2 is an enlarged front elevation, partly in 80 section, of the Bunsen tube and its pivotal connection to the supporting pipe; Figs. 3 and 4 are transverse sectional views taken along the lines 3—3 and 4—4 of Fig. 2; Fig. 5 is a detail side elevation looking from the 85 rear in Fig. 2 and showing the device for regulating the pilot flame; Fig. 6 is an enlarged detail view of the mantle holder; Fig. 7 is a side elevation of the burner tip; Fig. 8 is a transverse sectional view taken 90 along the line 8—8 in Fig. 7; and Fig. 9 is a partial sectional view taken along the line 9—9 in Fig. 2.

Referring to Fig. 1 we have shown our improved burner mounted upon a rigid pipe 95 10 having a valve 11 of any usual form connected thereto. An arm 12 is rigidly supported upon the pipe 10 and extends horizontally therefrom. At its outer end the arm 12 is bent upwardly and supports 100 a horizontal plate 13 which may if desired be formed integrally therewith. The plate 13 is provided with a plurality of depending projections 14 through which extend screws 15 for engaging and supporting a shade 16. 105 Upon its upper side, the plate 13 is pro-

vided with a plurality of fingers 17 which constitute means for supporting a reflector 18. A ring or band 19 of thin sheet material may encircle the arms 14, being secured thereto and concealing the upper edge of the shade 16.

The plate 13 is provided with a central circular recess 20 within which is supported the mantle holder 21. The holder 21 (Figs. 1 and 6) comprises a mantle ring 22 to which the mantle 23 is bound or otherwise secured. From the ring 22 a plurality of outwardly inclined arms 24 project upwardly in position to contact with the edge of the circular recess 20. At their upper ends the arms 24 may be connected by a reinforcing connection 25. The holder 21 is self-centering in the recess 20 and by changing the angle of the arms 24, a number of different sizes of mantles may be held in the same plate 13.

The burner tube 26 is pivotally connected to the rigid pipe 10, the outer end of the tube being initially movable upwardly in a substantially vertical direction out of the mantle 23 and thereafter movable about its pivot to the position indicated in dotted lines in Fig. 1. When the burner is thus removed, it will be seen that the mantle 23 and its holder 21 may be removed from their support by simply lifting them through the recess in the plate 13. It will also appear that the shade 16 can be removed downwardly and that the reflector 18 can be removed upwardly without disturbing either of the other elements.

A flanged plate 27 of the usual form may be provided upon the burner tube to partially cover the opening in the reflector 18 and the tube 26 may also be provided with a suitable burner tip, one form of burner tip suitable for use with a pilot light being shown in Figs. 7 and 8. Referring to said figures, the burner tip 28 comprises a substantially cylindrical wall 29 of magnesia or other suitable heat resisting material, said wall having a small passage 30 extending longitudinally therethrough at one side of the cylinder and communicating at its lower end with a narrow slot 31 extending transversely through the wall. At its upper end, the passage 30 connects with the end of a pilot tube 32. This form of burner tip possesses distinct advantages even when used upon a fixed burner tube of the usual form. The pilot flame being within the mantle and at the edge of the burner tip, the inflowing gas is immediately ignited and the danger of explosion within the mantle is greatly reduced. Furthermore by the location of the longitudinal passage within the wall of the tip we provide an entirely unobstructed gas opening through the tip and by extending the slot transversely through the wall a portion of the pilot flame is positioned at the

outer side of the tip where it cannot be extinguished by the rush of gas through the tube.

Referring to Figs. 1 and 2, we have shown the burner tube 26 connected to a Bunsen tube 33, of a well known type. This Bunsen tube comprises a substantially conical shell 34 having a small opening 35 at the upper end thereof. The pointed upper end 36 of a sliding plug 37 projects into the opening 35, the amount of such projection being determined by the regulating screw 38. A spring 39 may be provided within the shell 34 to force the plug 37 downwardly against the regulating screw.

The enlarged lower end of the plug 37 is provided with a plurality of notches or recesses 40 (Fig. 4) through which gas may pass to the opening 35. In our improved burner, we extend the pilot tube 32 (Figs. 7 and 2) around the curve of the tube 26 and enlarge one of the notches 40 to permit the passage of the tube therethrough.

A lug or screw 41 may be mounted upon the side of the Bunsen tube 33, projecting within the burner and coacting with a vertical groove 42 in the side of the plug 37, this arrangement permitting vertical movement of the plug but preventing angular movement, thereby securing the plug in position to permit the free passage of the tube 32. The pilot tube extends downwardly through the Bunsen tube 33 and is designed to have a close sliding fit into a cylindrical passage 43 (Fig. 2) in a sleeve 44 which constitutes one element of the pivotal connection between the Bunsen tube 33 and the fixed pipe 10. The Bunsen tube 33 is also designed to have a close sliding fit upon the outside of a cylindrical projection on the sleeve 44 and may be secured in position thereon by a screw 45 passing through the lower end of the burner and into a hole in the sleeve. With this construction, the parts may be assembled by a straight axial movement which will permit the easy insertion of the pilot tube 32 into the passage 43.

It is sometimes desirable to use the pilot flame as a night light, for which purpose the size of the flame should be increased. To permit easy adjustment of the pilot flame for either purpose we provide the screw 46 having a handle 47 and engaging either one of a pair of stops 48 adapted to position the handle in either the full line or the dotted line position shown in Fig. 5. The stops 48 may consist of eccentrically mounted disks which may be adjusted upon their pivot screws 49 for fine adjustment of the flame. The screw 46 extends into and partially closes the passage 43 (Fig. 9).

In the preferred form of our invention we provide a special fitting for supporting the sleeve 44 and the Bunsen tube 33 upon the pipe 10. Referring to Figs. 2 and 3, this

fitting comprises a casting 50 threaded or otherwise fixed upon the pipe 10 and having a vertical passage 51 communicating with a tapered opening 52 extending transversely through the upper end of the casting. A plug 54 provided with oppositely tapered ends is fitted into the opening 52 in the casting 50 and into the transverse opening in the sleeve 44.

10 The plug 54 is retained within the casting 50 by a screw 55 which engages a washer 56 and forces the same into frictional contact with the end of the casting 50. The washer 56 may be conveniently provided with arms 15 57 to which chain pulls 57^a may be attached for purposes to be described. At the opposite end of the plug 54 a screw 58 engages a washer 59 and forces the same against the end of the sleeve 44. The washers 56 and 20 59 are slideable but non-rotatable upon the end portions of the plug 54. In the actual operation of the device, the screws 55 and 58 are so adjusted that the friction between the washer 56 and the casting 50 shall exceed the friction between the washer 59 and the casting 44.

The plug 54 is provided with a central passage 60 communicating at its right hand end with a transverse passage 61 opening 30 into a circumferential groove 62. At its opposite end the passage 60 is closed by a suitable plug or by the screw 55 and connects with a second transverse passage 63. This passage is so positioned that when horizontally disposed, as in Figs. 2 and 3, no gas can pass through the passage 63 to the central passage 60 and therefore no gas can pass to the Bunsen tube. When the plug 54 is turned 90 degrees from the position shown 35 in Fig. 2 gas will pass freely through the passages 63, 60 and 61 and the groove 62 to a vertical passage 64 in the sleeve 44, the passage 64 opening into the gas chamber below the adjustable plug 37 of the Bunsen 40 tube 33. The plug 54 is also provided with two smaller circumferential grooves 65 and 45 66 which are connected through the body of the plug by a longitudinal passage 67 suitably closed at its outer end by a plug 68. The groove 65 is positioned to communicate 50 at all times with the opening 51 in the casting 50, while the groove 66 communicates with the passage 43 in the sleeve 44 through 55 which connection is made with the pilot tube 32. When the plug 54 is positioned as shown in Fig. 2, gas will pass freely through the groove 65, the passage 67 and the groove 66 to the passage 43 and tube 32, thereby 60 permitting the operation of the pilot light or night light when the main Bunsen tube is shut off.

It is desirable that the pilot light should be extinguished after the Bunsen flame is ignited, in order that a clear colorless flame 65 may be secured and accordingly we inter-

rupt the groove 66 by a closed portion or stop 70 which in certain positions of the plug 54 covers the lower end of the passage 43 through which gas is admitted to the pilot light.

In order that the plug 54 may be moved to admit gas to the Bunsen tube when the tube 26 is moved into the dotted line position shown in Fig. 1, we provide the sleeve 44 with a lug 71 projecting into a recess 72 in 75 the casting 50, and we also provide a pin 73 mounted in the plug 54 and engaging the upper side of the lug 71. When the burner is thrown back to its dotted line position, the lug 71 will move upward, as viewed in Fig. 2, carrying with it the pin 73 and turning the plug 54 through an angle of 90°. This movement of the plug allows the gas to pass through the Bunsen tube for ignition at the burner tip by the pilot light. After the 80 burner is thus lighted, it is returned to its normal position within the mantle but the plug 54 remains unmoved by this latter movement on account of the excessive friction between the washer 56 and the casting 90 50. The sleeve 44 therefore turns relatively to the plug 54, and the stop 70 is thereby brought into position to cover the passage 43 and shut off the pilot light. The burner thereafter remains lighted until the plug is 95 restored to its first position by proper manipulation of one of the chain-pulls 57^a attached to the arms 57. It will thus be seen that the lighting of the burner and the shutting off of the pilot light are accomplished by 100 merely moving the burner out of its normal position and thereafter returning it thereto.

While this automatic operation of the different valves is of great importance it will be evident that many of the advantages of 105 our invention do not depend upon the employment of this specific mechanism. For example, in a cheaper form of our device, we will omit the pilot light and will control the gas supply entirely by the valve 11, in which 110 case any common form of hinged gas connection may be substituted for the connection shown in Fig. 2.

Having thus fully described our invention, it will be evident that other changes 115 and modifications can be made therein without departing from the spirit and scope of our invention as set forth in the claims and we do not wish to be otherwise limited to the details herein described but

What we do claim is:—

1. An incandescent gas burner comprising a pipe, a frame fixed thereon and supporting a shade and a mantle, and a burner tube pivotally mounted on said pipe, and 125 movable into and out of operative relation with said mantle, said tube at all times retaining operative connection to said pipe, whereby said burner may be lighted while the burner tube is removed from the mantle. 130

2. An incandescent gas burner comprising a pipe, a mantle and holder mounted in fixed position thereon, and a burner tube also mounted on said pipe, the end of said tube being movable in a substantially vertical direction out of said mantle into convenient lighting position, said tube at all times retaining operative connection to said pipe, whereby said burner may be lighted while the burner tube is removed from the mantle.

3. An incandescent gas burner comprising a pipe, a frame fixed thereon, a mantle and mantle holder supported on said frame, and a burner tube movably mounted on said pipe, the outer depending end of said tube being positioned in operative relation to said mantle but removable upwardly therefrom in a substantially vertical direction to lighting position, whereby said burner may be lighted while the burner tube is removed from the mantle.

4. An incandescent gas burner comprising a pipe, a frame mounted thereon for supporting a shade and a mantle, and a burner tube pivotally mounted on said pipe, said tube being of substantially semi-circular form with its outer depending end normally positioned in operative relation to said shade and mantle and movable on its pivot in a substantially vertical direction away from its operative position to a lighting position substantially removed from said shade and mantle, said tube retaining operative connection with said pipe in all positions of said tube.

5. In an incandescent gas burner, a pipe, a frame fixed thereon, and means for separately supporting a shade, a mantle-holder, and a reflector on said frame, said shade, mantle-holder and reflector being each independently removable from said frame without movement of said frame or of the other two elements.

6. In an incandescent gas burner, means for supporting a mantle comprising a fixed plate having a substantially circular recess therein, and a mantle holder comprising a circular mantle ring, and a plurality of outwardly and upwardly inclined arms projecting from said ring and contacting with the edge of said circular recess, thereby centering the mantle in the recess.

7. An incandescent gas burner comprising a pipe, a Bunsen tube, a pilot tube, and a pivotal connection between said pipe, Bunsen tube and pilot tube, said connection comprising a casting mounted on said pipe, a sleeve secured to said Bunsen tube, and a plug frictionally fitting said casting and sleeve and angularly movable therein, said plug having passages therethrough, one of said passages opening into a circumferential groove at one end, which groove communicates with the pilot tube and has a

closed portion effective to close the end of said tube in certain angular positions of said plug.

8. An incandescent gas burner comprising a pipe, a frame mounted thereon for supporting a shade and a mantle, a burner tube pivotally mounted on said pipe and movable into and out of operative relation with said mantle, and pivotal connections between said pipe and burner tube, comprising an angularly movable plug having gas passages therethrough, and means movable with said tube and effective to move said plug to admit gas to the burner tube as the end of the tube is moved away from the mantle.

9. An incandescent gas burner comprising a pipe, a Bunsen tube, a pilot tube, and a pivotal connection between said pipe, Bunsen tube and pilot tube, said connection comprising a casting mounted on said pipe, a sleeve secured to said Bunsen tube, and a plug frictionally fitting said casting and sleeve and angularly movable therein, said plug having passages therethrough, communicating at one end with said pipe, and at the other end with said Bunsen tube and pilot tube, said plug also having a projection thereon, and said sleeve having a lug engaging one side of said projection, whereby said sleeve is effective to move said plug in one direction only.

10. An incandescent gas burner comprising a pipe, a frame mounted thereon for supporting a shade and a mantle, a burner tube pivotally mounted on said pipe and movable into and out of operative relation with said mantle, and pivotal connections between said pipe and tube comprising an angularly movable plug having gas passages therethrough, means movable with said tube, effective to move said plug to admit gas to the tube as the end of the tube is moved away from the mantle, and means for frictionally retaining said plug in its new position as the tube is returned to normal position.

11. An incandescent gas burner comprising a pipe, a frame mounted thereon for supporting a shade and a mantle, a burner tube pivotally mounted on said pipe and movable into and out of operative relation with said mantle, a pilot tube movable with said burner tube, and pivotal connections between said pipe and tubes comprising an angularly movable plug having gas passages therethrough, means movable with said tubes effective to move said plug to admit gas to the tubes as the end of the burner tube is moved away from the mantle, and means on said plug effective to close said pilot tube as the burner tube is returned to normal position.

12. In an incandescent gas burner, a burner tip comprising a cylindrical wall of

heat resisting material, said wall having a small passage extending longitudinally therethrough, and said passage communicating with a narrow slot at one end to said 5 tip extending transversely through said wall.

In testimony whereof we have hereunto

set our hands, in the presence of two subscribing witnesses.
